Int. Cl. D11—02

U.S. Cl. D35—3

FIG. 1

FIG. 2

FIG. 3

FIG. 4

FIG. 5

FIG. 1 is a side elevational view of a first embodiment of a plastic flower window planter showing my new design;

FIG. 2 is a top plan view thereof;

FIG. 3 is a bottom plan view thereof;

FIG. 4 is an end view thereof; and

FIG. 5 is a side elevational view of a second embodiment of such a planter, the over-all shape of this embodiment being similar to the embodiment of FIG. 1 with the exception of the defining contour of the faces.

I claim:

The ornamental design for a plastic flower window planter, as shown and described.
